UNITED STATES PATENT OFFICE.

JOHN F. CRAWFORD, OF RACINE, WISCONSIN, ASSIGNOR TO J. I. CASE THRESHING
MACHINE COMPANY, OF RACINE, WISCONSIN, A CORPORATION OF WISCONSIN.

METAL-BENDING MACHINE.

1353.635.

Specification of Letters Patent. Patented Sept. 21, 1920.

Application filed February 20, 1919. Serial No. 278,270.

To all whom it may concern:

Be it known that I, JOHN F. CRAWFORD, a citizen of the United States, residing at Racine, in the county of Racine and State 5 of Wisconsin, have invented certain new and useful Improvements in Metal-Bending Machines, of which the following is a specification.

My invention relates to improvements in
machines for forming rings from angle-iron
bars, such character of rings being com-
monly employed in the construction of farm
tractor wheels, which serve as felly bands
and the like, and for many other purposes,
and by which machine I am enabled to
readily insert therein a straight angle-iron
bar and quickly shape the same into true
ring form while retaining the webs of the
material in their original right angle rela-
tion, or may produce the ring with one of
its webs either at an obtuse or acute angle
in relation to the other, all as will be here-
inafter more particularly pointed out.

In the accompanying drawings, forming
25 a part hereof, Figure 1 is a front elevation
of my improved angle iron bending ma-
chine; Fig. 2 a plan view of the same; Fig.
3 a sectional view taken on the dotted line
3—3 in Fig. 1, looking in the direction indi-
30 cated by the arrows; Fig. 4 a detail sec-
tional view looking in the direction indi-
cated by the arrows 4—4 in Fig. 2; Fig. 5
a sectional view looking in the direction in-
dicated by the arrows 5—5 in Fig. 1; Fig.
35 6 a plan partially in section taken on the
dotted line 6—6 in Fig. 1; Fig. 7 a frag-
mentary plan similar to Fig. 6, but showing
some of the parts in changed position; Fig.
40 8 a plan and Fig. 9 a side elevation, respec-
tively, of the clamp for holding the angle-
iron to the disk forming part of my ma-
chine; Fig. 10 a diagrammatic view show-
ing two of said clamps holding the angle-
iron to the disk, the rolls for guiding said
45 material being shown in dotted lines; Fig.
11 a plan of the formed ring as it is de-
livered from the machine; and Fig. 12 is a
side view of the ring instantly it leaves the
machine but which by its inherent spring
50 force assumes its true position as indicated
in Fig. 11.

In said drawings the frame, 1, may be any suitable structure for the purpose, that shown comprising a base, 2, with pillars or 55 legs, 3, secured thereto and upon which are

mounted a table or platform, 4. Mounted upon said frame is a driving shaft, 5, provided at one end with a pulley, 6, driven by a belt, 7, the rotation of said pulley being controlled by a clutch mechanism, 8, through rod, 9, with hand lever, 10, for starting and stopping the machine. Mounted upon the opposite end of said shaft 5, is a beveled gear, 11, which meshes with a similar gear, 12, on shaft, 13, by which the latter is driven through the rotation of shaft 5, said gears being preferably inclosed within a housing, 12'. Shaft 13 carries a worm, 14, which meshes with a worm-wheel, 15, inclosed in casing, 15', said wheel being secured to a vertical shaft, 16, which at its lower end is mounted in thrust bearings, 17, and by which worm-wheel said shaft is actuated to rotate a disk, 18, secured at the upper side thereof by a collar, 19, to which it is preferably fastened by bolts, 20, said collar being keyed, at 21, to shaft 16, and which disk is driven in the direction indicated by the arrow in Fig. 6. I am thus enabled to readily remove and replace disk 18, which, it will be understood, varies in diameter according to the size of the ring to be rolled, and which disk is slightly less in diameter than such ring to be formed, for the reason that the angle-iron springs open slightly when being released from said disk.

In a chamber, 22, formed by a longitudinal trough-shaped wall, 23, which comprises a guide-way, 24, I mount a roller-head, 25, having legs, 25', adapted to be supported by and to travel along said guide-way, said head carrying rollers, 26, 27, 28, which head may be shifted in relation to disk 18 to provide proper space between said rolls and disk to accommodate angle-iron bars varying in thickness. The upper roll 26 is keyed at 29, to a spindle, 30, which rotates in tubular member, 31, of said roller-head, said member being pivotally mounted in the head, at 32. A hand wheel, 34, is provided to operate a screw, 35, for adjusting said roll 26 in relation to the top flange or web of the angle-iron bar, 36, to be developed into ring formation, by which means, as heretofore indicated, roller 26 may be raised and lowered the desired extent to come into contact with said angle-iron. The lower tubular member, 38, of said roller-head 25 comprises a casting similar to upper member 31, in which is carried a spindle, 39, 110

upon which is mounted the roller 27, which said roller, as will be observed in Fig. 4, is positioned underneath and supports disks 18 in its rotary movement. In addition to the 5 rolls 26 and 27 arranged and operating in the manner described, I provide a horizontally arranged roller, 28, in proximity to said rollers 26 and 27 and the periphery of which is in substantial registry with the inner 10 faces of said two rollers. This roller 28 is provided with studs, 40, 41, at its upper and lower faces, respectively, and which are seated in recesses in the members 31 and 38, which recesses serve as bearings therefor, as 15 indicated in Fig. 4. It will be understood that said rollers 26, 27, 28 are in effect idlers upon the different bearings upon which they are mounted, but when disk 18 is rotated, and as angle-bar 36 is inserted between it 20 and said rollers, the rotary action of said disk carries said bar between said rollers and because of the frictional engagement between all of said parts said rollers rotate and assist said disk in feeding and carrying 25 said angle-iron around with the said disk in the direction of its travel, thus having the effect of binding and shaping said angle-iron against the disk and forming the same curvilinearly to conform to the circular 30 tour of said disk 18. As a simple means for adjusting the roller-head 25 in entirety in relation to disk 18, I provide a link, 45, pivoted, at 46, in the head, 25, and at 47 to a hand-lever, 48 (Fig. 4), said hand-lever 35 being pivoted to a lever-plate, 50, by a stud, 51, driven into and connecting both, said lever-plate being mounted and resting in guide-way 24. Interposed between said hand-lever 48 and lever-plate 50 is a clamp- 40 ing-plate, 52, which is carried with said structure and wedges the lever-plate into the guide-way by the bolts, 53. By reference to Fig. 4 it will thus be seen that the manipulation of the hand-lever 48 serves to 45 adjust the roller-head longitudinally along said guide-way, which adjustment is of limited movement, and in order to prevent extreme play of the link 45 a set screw, 54, is mounted in member 31 which may be ad- 50 justed to control the lateral movement of said link.

As a positive means for correctly feeding angle-iron bars into my improved machine to be formed into rings, I prefer to employ 55 an air cylinder, 58, which actuates a plunger, 59, having a rack, 60, near its end which meshes with a segment, 61, pivoted at 62, to a casting or segment support, 63, which segment also carries an arm, 64, supporting 60 at its upper end a roller guide 65, and beneath said guide 65 is provided with a stud, 65', upon which is mounted an angle-bar guide, 66, the front end of which latter guide rests above disk 18. A hand lever, 67, 65 pivoted to segment support 63 is connected

by a rod, 68, to a valve (not shown) in the air pump 58 and by which said air pump is set in operation to actuate plunger, 59, the longitudinal movement of said plunger being limited by an adjustable set-screw, 69, or 70 otherwise, by which its stroke is regulated.

When forming a ring from an angle-iron bar as 36, the same is inserted between guide 66 and roller 65 (Fig. 5), and the former is slightly raised by manipulating lever 67 to 75 cause plunger 59 to actuate segment 61 and raise said guide 66 and roller 65. The end of said bar 36 is projected between the rollers 26, 27, 28, (Fig. 7), assuming a horizontal position therebetween, and by the rotation of disk 18 is drawn under a pivoted clamping wedge, 70, (Fig. 6), which is adapted to be inserted in any one of several apertures, 71, in said disk, and which clamping wedge is provided with a roughened or gripping face 72, and a post, 73, for insertion into said disk. In the upper member 31 a manually adjustable dog, 74, is pivotally mounted as at 75, and by a handle, 76, is caused to engage the hooked end of 80 clamping wedge 70, and as the end of angle-bar 36 is inserted under the clamps the gripping face thereof is thrown against the bar by operating dog 74, and said bar is thus seized and clamped by said wedge, the rotary motion of disk 18 drawing said bar about its periphery and by the contact of said wedge with dog 74 wedges or clamps said bar. Simultaneously with said movement the wedge 70 gradually turns said dog 100 74 on its pivot until it becomes released therefrom and passes from within its influence, and remains in the position shown in Figs. 6 and 10, and constantly maintains the bar in position about the periphery of 105 said disk. As disk 18 continues to rotate, in order to insure uniform retention to said disk of the bar undergoing ring formation I may insert additional clamping wedges about the disk, as for instance as indicated 110 in Fig. 10, so that when the bar has been completely fed between the rolls and thus held in fixed position about the disk a substantially perfect ring, 80, will be produced from such straight bar and the ends of 115 which will approximately meet as indicated in Fig. 11.

In practice it is found desirable for some purposes to form rings of this character with the vertical web or flange arranged at 120 an obtuse or acute angle in relation to the upper or horizontal web. When bar 36 is inserted in guide 66, and the latter is in normal position as indicated in Fig. 3, upon being grasped between disk 18 and rolls 26, 125 28, the vertical web thereof is drawn into a slightly acute angle in relation to its horizontal web, which relation it will maintain when in ring formation. By slightly raising guide 66 and thus stretching the vertical 130

web the latter is brought from such acute to a true angle as the bar passes through the disk and rolls, so that either formation may be readily obtained. However, if a slightly obtuse angle is desired this is obtained by raising the guide 66 higher, as indicated in Fig. 5, which permits a greater stretching of the web, and even though said disk and rolls impart a constant grip to said vertical web the tension in the metal will spring it back to the shape required, as I have demonstrated in the practical operation of my improved bending machine. The degree of angularity may be determined by the requisite regulation of said feeder in the operation of the machine, but it will be understood that because of the formation of said disk and rolls such angular relation of the vertical web is limited, and to permit of a greater range such elements should be beveled to a certain extent.

In the manner illustrated and described I provide a substantially simple arranged machine for rapidly forming rings from angle-iron bar material comprising a system of adjustable rotary elements and clamping devices by which unskilled assistants may readily produce such rings with a minimum of effort and attention, and which elements may be quickly adjusted to accommodate angle-iron material of varying sizes in thickness and width of webs.

I claim as my invention:

1. In a machine for forming angle-iron rings, the combination of a frame, a rotary disk mounted thereon, a roll upon which said disk travels and is frictionally driven thereby, a vertically adjustable roll above said disk, a horizontally positioned roll intermediate said rolls, said adjustable and intermediate rolls being adapted to retain angle-iron material between them and said disk, and means for rotating said disk to propel said material and rotate said adjustable and intermediate rolls through frictional engagement with said material.

2. In a machine for forming angle-iron rings, the combination, with a frame, of a rotary disk, means for rotating the same, a vertically adjustable roll mounted above said disk for gripping an angle-iron web against the same, means for adjusting said roll, a roll beneath said disk for supporting the same, and a horizontally positioned roll intermediate said rolls and adjacent the periphery of said disk for gripping an angle-iron web thereagainst.

3. In a machine for forming angle-iron rings, a roller-head comprising an upper cylindrical member, a spindle therein, a roll mounted at one end of said spindle, means for raising and lowering said cylindrical member to adjust said roll, a cylindrical member beneath said adjustable member, a spindle therein, a roll at the end of said

spindle, a bearing in said lower cylindrical member, and a horizontally positioned roll mounted therein.

4. In a machine for forming angle-iron rings, a roller-head comprising an upper cylindrical member, a roll mounted therein, a lower cylindrical member, a roll in said lower member, a horizontally positioned roll intermediate said rolls and a guide-way upon which said head is mounted and by which said rolls may be adjusted.

5. In a machine for forming angle-iron rings, a roller-head comprising members carrying upper and lower rolls and an intermediate horizontally positioned roll, a guide-way over which said head is mounted, means connected to said roller-head and slidably supported in said guide-way, and means for actuating said roller-head to be adjusted along said guide-way upon its supporting means.

6. In a machine for forming angle-iron rings, a rotatable disk, a removable clamping wedge having vertically arranged pivotal means insertible in said disk, a substantially horizontally arranged member extending therefrom, and a vertically arranged clamping face spaced from said pivotal means and adapted to extend downwardly over the periphery of said disk for wedging material against said disk.

7. In a machine for forming angle-iron rings, a rotatable disk, a roller-head comprising a plurality of rolls coöoperating with said disk for binding angle-iron thereto, an adjustable clamp mounted in said disk for clamping material thereto, against the periphery thereof, and a pivotally mounted dog arranged to engage said clamp to adjust the same in clamping position.

8. In a machine for forming angle-iron rings, a frame, a tubular member mounted in said frame, a spindle therein, a roll at one end of said spindle, a tubular member below said first member, a spindle therein having a roll mounted upon its end, a rotatable disk coöoperating with said rolls, and means for adjusting said members, spindles and rolls longitudinally of said frame.

9. In a machine for forming angle-iron rings, a frame, a rotatable disk mounted therein, a roll beneath said disk for supporting the same, a vertically arranged roll above said disk, a horizontally arranged roll adjacent said vertically arranged roll and coöoperating therewith and with said disk for retaining an angle-iron bar against said disk, and a guide for directing the insertion of such bar between said disk and rolls.

10. In a machine for forming angle-iron rings, a frame, a rotatable disk mounted therein, a roll beneath said disk for supporting the same, a vertically arranged roll above said disk, a horizontally arranged roll adjacent said vertically arranged roll

and coöperating therewith and with said disk for retaining an angle-iron bar against said disk, and an adjustable guide for directing the insertion of such bar between said disk and rolls.

11. In a machine for forming angle-iron rings, a frame, a rotatable disk mounted therein, a roll beneath said disk for supporting the same, a vertically arranged roll above said disk, a horizontally arranged roll adjacent said vertically arranged roll and coöperating therewith and with said disk for retaining an angle-iron bar against said disk, a guide for directing the insertion of such bar between said disk and rolls; and means for adjusting said guide to raise and lower said bar while being inserted.

12. In a machine for forming angle-iron rings, a frame, a rotary disk mounted therein, a roll beneath said disk for supporting the same, a vertically arranged roll above said disk, a horizontally arranged roll adjacent said vertically arranged roll and coöperating therewith and with said disk for retaining an angle-iron bar against said disk, an adjustable guide for directing the insertion of material between said disk and rolls, and means for clamping such material about said disk when assuming ring formation.

13. In a machine for forming angle-iron rings, a horizontally arranged rotatable disk, a roller-head comprising vertically arranged rolls coöperating therewith for shaping angle-iron, a guide for directing material to said rolls, a pivotally mounted segment connected to said guide, and means for actuating said segment to adjust said guide.

14. In a machine for forming angle-iron rings, a rotatable disk, a roller-head comprising rollers coöperating therewith for shaping angle-iron, a guide for directing material into said rolls and disk, adjustable means for supporting said guide, and a roller associated with said guide and coöperating therewith for directing material to said rolls and disk.

15. In a machine for forming angle-iron rings, a rotary disk, a roller-head adjacent said disk carrying rolls for coöperating therewith to bind an angle-bar thereto, a clamp supported in said disk for binding such bar thereto, and means carried by said head for engaging said clamp to adjust the same against said bar.

16. In a machine for forming angle-iron rings, a rotary disk, a roller-head adjacent said disk carrying rolls for coöperating therewith to bind an angle-bar thereto, a clamp supported in said disk for binding such bar thereto, and a dog pivotally mounted in said head for engaging said clamp to adjust the same against said bar.

17. In a machine for forming angle-iron rings, a rotatable disk for carrying an angle-bar, a guide for feeding such bar to said disk, rolls coöperating with said disk for binding such bar thereto; an arm for supporting said guide, a segment connecting with said arm, a cylinder having a plunger engaging said segment, and means connected to said cylinder for operating said plunger to actuate said segment and raise or lower said guide.

18. In a machine for forming angle-iron rings, a frame, a driving shaft supported thereby, a rotary disk mounted on said frame, means connecting said shaft and disk for rotating the latter, a roller for supporting said disk, a vertically arranged roller above said disk, a horizontally arranged roller adjacent said vertically arranged roller, said vertical and horizontal rollers coöperating with said disk for bending material therebetween, means for feeding material to said disk and rollers, adjustable means carried by said disk for clamping material against the periphery thereof, and means for adjusting said rollers in relation to said disk for accommodating angle-iron of varying thickness.

In testimony whereof I affix my signature.

JOHN F. CRAWFORD.
